UNITED STATES PATENT OFFICE.

WILLIAM S. BOYCE, OF CHICAGO, ILLINOIS.

TIE PLATE.

Application filed November 14, 1925. Serial No. 68,950.

This invention relates to tie plates and more particularly to the means for holding the plate against longitudinal movement relative to the tie, without destruction or damage to the tie, and to means to afford drainage from beneath the plate, and reduce the cost.

The invention is applicable to tie plates of various configurations, but the basic idea thereof will be more readily understood by the accompanying drawings, in which I have chosen to represent the invention as applied to the form of plate covered by United States Letters Patent, Reissue No. 15,989, granted to me and dated January 27, 1925.

In the evolution of track conditions and rolling stock, the constantly increasing heavier train loads are accompanied by a demand for heavier rail sections and heavier tie plates. Tie plates, without regard to their special conformations, are therefore becoming larger in surface dimensions, and the thickness at those portions where the greatest strain and stress are put upon them is constantly increasing to avoid all tendency to break or buckle. As plates are generally sold by weight, it is highly desirable to make a plate of maximum thickness at these critical portions, while at the same time save as much metal as possible by making the plate relatively thinner at less critical portions. This object has been difficult of attainment because of the necessity of having tie penetrating projections or ribs on the bottom of the plate which would resist thrust and the movement of the plate on the tie, without making such projections and ribs of such character and size as to damage the tie and permit water to seep in and spread into the tie on either side of the grooves or indentations in the tie made thereby.

In the plate shown in my said reissued Patent No. 15,989, the thickness of the plate from its top, rail bearing surface, to the surface of the relatively narrow, initially seating, tie bearing surfaces of its bottom, may be varied to meet any condition of track or track loads, but the amount of metal removed from the bottom to make the median and the end recesses is limited by the necessity of having configurated shoulders of the proper depth to resist relative

movement between tie and plate. If these resisting surfaces be too great, due to increasing the depth of the recessed portions, then the ribs or members forming such resisting surfaces have to be made sharp pointed or of other tie penetrating configuration of corresponding or greater depth than that of the recesses, and this unduly cuts, weakens and damages the ties.

In the following description of my invention, it will be seen that this difficulty is avoided, that I may have a plate of the maximum thickness at the points where thickness is required, a plate having movement-resisting shoulders of the requisite depth to correspond with the maximum thickness of the plates at the points mentioned: while, at the same time, I reduce the weight of the plate, removing surplus metal by increasing the depth of the recesses and making the body of the plate above the recesses, relatively thinner, and all without increasing the tendency of the tie penetrating portions to injure the tie.

My invention consists of the devices and combinations of devices herein illustrated, described, and more particularly pointed out in the appended claims.

In the accompanying drawings:

Figure 1 is a perspective view of a tie plate embodying my invention.

Figure 2 is a longitudinal sectional view of the same, on an enlarged scale.

Figure 3 is a bottom plan view of the same.

Figure 4 is a transverse, sectional view of the same, the section being taken in the vertical plane indicated by the dotted line 4—4 on Fig. 2.

Figures 5 and 6 are bottom plan views of modifications of the form of bottom shown in Fig. 3.

Figure 7 is a perspective view, on a still larger scale, showing the top of a railroad tie as formed by the seating of the form of plate illustrated in Figs. 1 to 4,—the plate of course being removed.

Figure 8 is a bottom plan view of another modification.

Figure 9 is a side view of the modification shown in Figure 8, with a vertical section of a tie in which it has been seated.

The tie plate embodying my invention is

designated as a whole by the letter A and may have a top, tie bearing surface 1 of any desired configuration, and an upwardly extending, transverse rib 2, the face of which constitutes a rail abutting shoulder for the edge of a rail flange. As shown, this top surface is plain, and canted and cambered.

Its bottom is provided with two, spaced apart and relatively narrow members 3 which extend transversely of the plate A. The bottom at each end, 4, 5, beyond these relatively narrow members 3, is cut away or recessed as indicated by the numerals 6, 6. The bottom of the plate, intermediate the spaced-apart members 3, is also cut away or recessed as indicated at 7. This central or median recessed portion may or may not be provided with longitudinally extending, tie penetrating projections or ribs 8 shown. Upon the surface 9 of each narrow transversely extending member 3, I provide a downwardly extending, rib or projection 10, which extends lengthwise of the member 3 and therefore transversely of the plate. This projection or rib 10 will be formed with side faces or shoulders 11, 11, which converge to a rounded, blunt or non-cutting edge 12.

When this plate is laid upon a tie, a slight tap of a sledge will be sufficient to cause these projections or ribs 10 to indent the top surface of the tie sufficiently to hold the plate in position, while the rail is being laid and spiked to the tie. The initial train load passing over the truck will cause the initial seating of the plate on the tie, by pushing the relatively narrow members 3 into the tie. Thus the surface 9 of the members 3 becomes the initial tie bearing surface of the plate, and as such, is sufficient to hold the load and prevent bending or buckling of the plate A, as explained in my aforesaid reissued patent. Upon the passing of further train loads, the plate is embedded more and more into the tie until it finally becomes fully seated with not only the surfaces 9 but the cut away surfaces of the ends and of the median portion all resting firmly on the tie.

By the use of the projections or ribs 10, 10, however, it will be manifest that the thickness of the relatively narrow members 3 as well as the depth of the cuts or recesses, indicated at 4, 7 and 5, may be appreciably greater than would be possible in a serviceable plate without the projections 10, 10; and consequently, the thickness of the plate above its cut away portions will be less with, than without, said projections 10, 10, while the thickness of the plate from the top rail bearing surface 1 to the bearing surface 9 of the narrow members 3 will not be decreased, but may in fact be increased as desired.

The saving of metal by decreasing the

thickness of the plate through its ends and its median portions only one-sixteenth of an inch (in a plate $7\frac{1}{2}'' \times 10''$), effects a most substantial reduction in cost per mile to a railroad using such plates. This saving is over \$33.00 per mile, figuring plates at \$50.00 per ton.

Again the area of the bearing surfaces of the plate, embedded in the tie and acting to prevent relative movement between tie and plate, is not a matter of hazard, but of careful engineering computation; and since the dimension of length of such surface is limited to the width of the plate, the dimension of height of these movement-resisting surfaces is, therefore, of importance. If too little, it may not correlate properly to hold the plates, and if too great, it means too much penetration into and damage to the tie, and yet the heavier the plate and the greater the thickness at the points between the surfaces 1 and 9, where the greatest tendency to bending and breaking exists, the greater the requirement to have a proper area and proper tie penetration of shoulders or bearing surfaces to resist relative movement between tie and plate.

To meet this engineering requirement, I have conceived what in use is a very practical and efficient arrangement. I make the depth of the projection or rib 10 substantially equal to the thickness of the member 3. Thus the action of the bearing surfaces 13, 13, at the sides of the members 3, to resist relative movement of plate and tie, is supplemented by the action of the bearing surfaces 11 of the ribs 10, they together being of an area sufficient to meet the calculated requirements, and neither entering the tie an objectionable distance.

That is to say, if the requisite area for such bearing surfaces for a given plate may, by way of illustration, be represented by z , I make the area of the surface 11 plus the area of the surface 13 equal z requirement.

The rounding of the corners of the members 3 and the rounding of the edge of the ribs 10, although extending across the grain of the tie, do not cause a cutting or severing of the fibres, but a mere indenting and compressing action which compacts the fibres and forms a smooth and hard surface on the tie beneath the plate,—thus prolonging the life of the tie to a very measureable and desirable extent.

To still further cooperate in the saving of metal by increasing the depth of the median recess 7 and at the same time preserving the necessary strength of the body of the plate throughout its median portion, I use a plurality of parallel or separated, longitudinally disposed, ribs 8, which extend from the inner shoulders 13 of the members 3 toward the central median line or axis of the recessed area 7, and are of diminishing width

and height. These ribs 8 are substantially V-shaped in cross section as shown in Figure 4 and, preferably, are sharp or pointed, but their tie-entering edge is rounded as shown at 14. These ribs are in alignment, i. e. separated end to end, and their longitudinal direction may be either parallel with the sides of the plate, as shown in Fig. 3, or may extend angularly, as in the modification illustrated in Fig. 5.

The recessed ends of the plate may be flat as illustrated in Figure 3, or one or both ends may be provided with ribs 15 similar to the ribs 8, and diminishing in width and height from the outer edge of the member 3 to the plate end.

In the modification shown in Figure 8, I use a V-shaped rib 16 having a blunt or rounded tie-entering edge, which I locate in the median portion of the recessed part 7, said rib 16 extending transversely of the plate, preferably from side margin to side margin as shown, and parallel with the members 3, 3.

In addition to the advantages heretofore mentioned, my improved plate possesses the further advantage in all of the forms shown, of facilitating drainage of any water which may find itself between the plate and the tie. By reference to the tie shown in Figure 7, it will be seen that after my plate has been embedded or finally seated thereon, the fibres of the tie T have been shifted, compressed and formed into a set of drainage grooves by which the water will be eliminated. Water which may get under the central portion of the plate will run in two directions through grooves B formed in the tie by the ribs 8 and into one or the other of the grooves C formed by the members 3 and the grooves D formed by the blunt ribs 10. The grooves C and D extend, as shown, transversely of the tie. Water under the ends of the plate will drain to grooves C.

Where the plate is formed with a transverse rib 16 as shown in the modification illustrated in Figures 8 and 9, there will be an additional transverse drainage groove E formed in the top of the tie, as shown in the lower part of Figure 9.

Where the plate is cambered or bent, as indicated at 17 (Figures 1 and 9) and the bottom correspondingly bent, as for example, when a plate initially rolled flat is bent or cambered during the spike-hole punching operation, the top surface of the tie will finally assume a correspondingly crowned top and in such instances the grooves C, D and E being higher in the center than at each end, will facilitate drainage of water in each direction towards the sides of the tie.

The longer such a plate is in use, the more hard and compact will be the configurated top surface of the tie beneath it and there-

fore moisture, which otherwise would be inclined to seep into the tie, does not damage or rot the tie.

Spike holes 18 may be provided as desired.

It will be understood that ribs 8, 8 extending from opposite sides of the median recess 7 towards each other, form in a sense a truss, which very greatly strengthens the plate body and enables me to make the recess 7 relatively deeper even than shown, the drawing being illustrative merely.

I claim as my invention:

1. A tie plate having its bottom median portion and its bottom end portions cut away or recessed, a relatively narrow, initially tie-bearing member transversely of the plate and separating the end portion from the median portion, and a short tie embedding rib depending lengthwise from the relatively narrow, tie-bearing member.

2. A tie plate having its bottom median portion and its bottom end portions cut away or recessed, a relatively narrow, initially tie-bearing member transversely of the plate and separating the end portion from the median portion, and a short, blunt edged rib depending from and extending lengthwise of the relatively narrow tie bearing member.

3. A tie plate having its bottom median portion and its bottom end portions cut away or recessed, a relatively narrow, initially tie-bearing member transversely of the plate and separating the end portion from the median portion, and a shallow rib having a rounded or non-cutting edge depending from and extending lengthwise of the relatively narrow tie bearing member.

4. A tie plate having its bottom median portion and its bottom end portions cut away or recessed, a relatively narrow, initially tie-bearing member transversely of the plate and separating the end portion from the median portion, and a shallow rib having a rounded or non-cutting edge depending from the extending lengthwise of the relatively narrow tie bearing member, the depth of the median recess being less than the thickness of the relatively narrow members and the thickness of the shallow rib combined.

5. A tie plate having its bottom median portion and its bottom end portions cut away or recessed, a relatively narrow, initially tie-bearing member transversely of the plate and separating the end portion from the median portion, and a short tie embedding rib depending lengthwise from the relatively narrow, tie-bearing member, the sides of the rib and the sides of the relatively narrow tie bearing members constituting shoulders to resist relative movement between the plate and the tie.

6. A tie plate having a relatively wide,

transversely extending recess in the median portion of the bottom, and a plurality of tie engaging, depending ribs in said recessed portion, each rib being of decreasing width and height as it approaches the center of the recess and extending, substantially, longitudinally of the plate.

7. A tie plate having a relatively wide, transversely extending recess in the median portion of the bottom, and a plurality of tie engaging, depending ribs in said recessed portion, each rib being of decreasing width and height as it approaches the center of the recess and extending, substantially longitudinally of the plate, and having a non-cutting or blunt tie entering edge.

8. A tie plate having a relatively wide, transversely extending recess in the median portion of the bottom, and a plurality of tie engaging, depending ribs in said recessed portion, each rib being of decreasing width and height as it approaches the center of the recess and extending, substantially longitudinally of the plate the ribs being spaced apart longitudinally and separated laterally.

9. A tie plate having a relatively wide, transversely extending recess in the median portion of the bottom, and a plurality of tie engaging, depending ribs in said recessed portion, each rib being of decreasing width and height as it approaches the center of the recess and extending, substantially longitudinally of the plate, said ribs extending from two sides of the recess towards the middle and spaced apart endwise at their small ends.

10. A tie plate having a relatively wide, transversely extending recess in the median portion of the bottom, and a plurality of tie engaging, depending ribs in said recessed portion, each rib being of decreasing width and height as it approaches the center of the recess and extending, substantially longitudinally of the plate, said ribs extending in substantial parallelism transversely of the plate and from each side of the recess towards the middle thereof and being spaced apart endwise at their small ends.

11. A tie plate having a relatively wide, transversely extending recess in the median portion of the bottom, and a plurality of tie engaging, depending ribs in said recessed portion, each rib being of decreasing width and height as it approaches the center of the recess and extending substantially longitudinally of the plate, and a centrally and transversely positioned rib located intermediate the tapered ribs.

12. A tie plate having a relatively wide, transversely extending recess in the median portion of the bottom, and a plurality of tie engaging, depending ribs in said recessed portion, each rib being of decreasing width and height as it approaches the center

of the recess and extending, substantially longitudinally of the plate, said ribs extending from two sides of the recess towards the middle and spaced apart endwise at their small ends, and a centrally and transversely positioned rib located intermediate the tapered ribs.

13. A tie plate having a relatively wide, transversely extending recess in the median portion of the bottom, and a plurality of tie engaging, depending ribs in said recessed portion, each rib being of decreasing width and height as it approaches the center of the recess and extending substantially longitudinally of the plate, said ribs extending in substantial parallelism transversely of the plate and from each side of the recess towards the middle thereof and being spaced apart endwise at their small ends, and a centrally and transversely positioned rib located intermediate the tapered ribs.

14. A tie plate having a relatively wide, transversely extending recess in the median portion of the bottom, and a plurality of tie engaging, depending ribs in said recessed portion, each rib being of decreasing width and height as it approaches the center of the recess and extending, substantially longitudinally of the plate, and a plurality of similar ribs under the recessed plate end.

15. A tie plate having a relatively wide, transversely extending recess in the median portion of the bottom, and a plurality of tie engaging, depending ribs in said recessed portion, each rib being of decreasing width and height as it approaches the center of the recess and extending, substantially longitudinally of the plate, and a plurality of similar ribs under the recessed plate end, each of said end ribs also having a non-cutting tie entering edge.

16. A tie plate having on its bottom two relatively narrow, spaced apart, transversely extending, initially tie bearing surfaces, and a shallow, blunt rib depending from each, a plurality of ribs in the recessed portion of the plate between the relatively narrow surfaces and extending from said surfaces towards the center of said median recessed portion and decreasing in width and height towards the center, each rib having a blunt, non-cutting edge, and similar ribs on the recessed end portion of the tie.

17. A tie plate having the median and the end portions of its bottom cut away and separated by relatively narrow, spaced-apart tie bearing surfaces to initially seat upon the tie, and tie entering truss ribs in the median recessed portion extending transversely thereof and lengthwise of the plate.

In testimony, that I claim the foregoing as my invention I affix my signature this 11th day of November, 1925.

WILLIAM S. BOYCE.
